UNITED STATES PATENT OFFICE.

GEORGE HENRY, OF LENNOXVILLE, QUEBEC, CANADA.

MEANS FOR CONTROLLING THE SUPPLY OF ELECTRIC CURRENTS.

No. 923,839.

Specification of Letters Patent.

Patented June 8, 1909

Application filed February 2, 1907. Serial No. 355,453.

To all whom it may concern:

Be it known that I, GEORGE HENRY, of Lennoxville, Province of Quebec, Canada, have invented certain new and useful Im-
5 provements in Means for Controlling the Supply of Electric Currents; and I do hereby declare that the following is a full, clear, and exact description of the same.

This invention relates to automatic means
10 for controlling the supply of electric current sold to consumers for a fixed annual pay-
ment, particularly where there are a large number of consumers each of whom uses only a small number of lamps or the like, and
15 the object of the present invention is to pro-
vide an automatic device which shall be sim-
ple in construction, (comprising very few parts) and which shall be capable of accom-
modating different predetermined loads and
20 of adjustment to suit a change of load with-
out the removal and substitution of parts.

Up to the present in devices of this class there has been no provision for any increase in capacity nor has there been any conven-
25 ient means of adjustment to more than one predetermined load and any change in the carrying capacity could only be effected by removing a part of the device, the circuit maker and breaker, and substituting another
30 circuit maker and breaker to suit the differ-
ent load. Also having the object of sim-
plicity and cheapness of construction in view I have endeavored as far as possible to utilize ordinary stock for certain parts and to have
35 the parts readily accessible to facilitate manufacture and adjustment.

The invention may be said briefly to consist of a device to automatically open and automatically close the circuit and such de-
40 vice comprises a base, two circuit terminals, a lever fulcrumed near one of its ends to pre-
sent a short arm and a long arm, the latter carrying a contact to normally engage one of said terminals, a thermo-expansive wire hav-
45 ing one end secured to the short arm of the lever and its other end connected with the second of said terminals, the long arm of the lever having an adjustable tension device attached to its free end to operate the lever
50 and open the circuit upon the expansion of the thermo-expansive wire.

The invention further consists of an auxiliary conducting wire paralleling the expansive wire and adapted to carry a portion of the current when it is desired that a greater

quantity of current shall be accommodated than can be carried by the thermo-expansive operating wire alone.

For full comprehension, however, of the invention reference must be had to the accom-
panying drawings wherein:

Figure 1 is a plan view; Fig. 2 an end elevation and Fig. 3 a side elevation of my im-
proved device, Fig. 4 being a diagrammatic view of a local lighting circuit with the de-
vice applied thereto.

Upon a suitable base *k* are arranged terminal plates *j* and *r* from which at one end of each project binding posts *n* and *s*, respec-
tively, to which are detachably connected in
the customary manner the leading-in wires
5, 5, of the circuit, while the opposite ends of
said plates present posts *c* and *q* respectively,
and in this latter is carried an adjustable
screw bolt *p* carrying a platinum tip *p'* to
75 form the terminal contact of this part of the
circuit.

In order to provide a simple and effective means for not only automatically opening
80 the circuit when an attempt is made to se-
cure more than the stipulated amount of cur-
rent, but also to automatically close the cir-
cuit upon the resumption of normal condi-
tions I employ a circuit making and breaking
85 device as hereinafter described. A lever *e*
preferably formed of a simple length of brass
bar carrying a platinum contact tip *o*, to en-
gage the terminal contact tip *p'*, is fulcrumed
at *a* near one of its ends to the base *k*, thus
being divided into a comparatively very long
90 arm portion *e'* and a very short arm portion
*e*², for a purpose presently to be described.
To the short arm *e*² of the lever is secured
through a pin *d*, one end of a thermo-expansive
95 wire *b*, the other end of which is adjust-
ably connected with the post *c*, rising from
the terminal plate *j* before mentioned, by
means of a threaded bolt *h*, working through
an aperture in the post *c* and having a hooked
end *g* to which the wire *b* is secured, a nut *m*
100 on the bolt *h* serving to regulate the position
of the latter and through it the tension of the
wire *b*.

The parts of the device thus far described
serve only to effect the automatic closing of
105 the circuit and the parts for automatically
opening same consist of a retractile spring *f*
having one end secured to a pin *t* projecting
from the end of the long arm *e'* of the lever *e*,
and the other end attached to a threaded ad-

justing bolt *u* which passes through an aperture in a post *v*, rising from the base, and carries a nut *w* for adjustment.

As already pointed out the lever is fulcrumed so as to afford a long arm portion *e'* and the long pull off leverage thus secured, together with the platinum contact tips, is for the purpose of preventing as far as possible any chance of the contacts fusing together under any conditions, because it will readily be seen that owing to the comparatively great leverage a very slight force exerted by the retractile spring *f* will be sufficient to operate the lever and open the circuit when the thermo wire lengthens by expansion through carrying an excess of current.

In order to prevent lateral displacement of the lever and at the same time restrict the movement thereof under the influence of the spring *f* the pin *t* is straddled by a pair of pins *x* carried by a small insulated standard *y* screwed into the base, the standard limiting the said movement of the lever.

25 In order to accommodate when desired a greater quantity of current or larger predetermined load than can be carried by the thermo-expansive wire alone without opening the circuit, I provide an auxiliary wire 2, 30 permanently free from tension and having its ends connected by screws 3, 3, to the lever and the plate *j*, and the necessary adjustment to suit the change in the carrying capacity can very readily be effected by 35 altering the tension of the retractile spring *f*, through the nut *w*, and threaded bolt *u*, instead of by substituting for a spring of given inherent elasticity, suitable only for a given load, another spring of greater or less inherent elasticity as in the devices hitherto disclosed.

What I claim is as follows:—

1. In means for controlling the supply of electric current the combination with an 45 electric circuit of a circuit making and breaking device adapted to automatically close after it has been opened, said device including a stationary contact, a rigid lever carrying a contact, a pull off spring for said lever, 50 a thermo-expansive wire controlling the opening and closing of the circuit between said contacts and an adjusting device for regulating the pull off, or breaking, force of the lever, substantially as described.

55 2. In means for controlling the supply of electric current the combination with an 60 electric circuit of a circuit making and breaking device adapted to automatically close after it has been opened, said device including a stationary contact, a rigid lever carrying a contact, a pull off spring for said lever, a thermo-expansive wire controlling the opening and closing of the circuit between said contacts, an auxiliary wire for carrying 65 part of the current, and an adjusting device

for regulating the pull off, or breaking, force of the lever, substantially as described.

3. In means for controlling the supply of electric current, the combination with an 75 electric circuit, of a circuit making and breaking device adapted to automatically open and close said circuit and comprising a base, two circuit terminals, a lever fulcrumed near one of its ends to provide a long arm and a short arm the long arm being adapted to normally bear on one circuit terminal; a thermo-expansive wire connected at one end to the short arm of the lever and at the opposite end to the other circuit terminal; and an adjustable pull-off device for said lever comprising an apertured post carried by the base, a threaded bolt passed through the aperture in said post, a retractile spring having one end attached to the end of the long arm of the lever and the other end attached to the threaded bolt, and an adjusting nut on said bolt, substantially as described.

4. In means for controlling the supply of electric current, the combination with an 90 electric circuit, of a circuit making and breaking device adapted to automatically open and close said circuit and comprising a base, two circuit terminals, a lever fulcrumed near one of its ends to provide a long arm and a short arm and carrying a contact tip on its long arm near the fulcrum point to normally bear on one circuit terminal, a thermo-expansive wire connected at one end to the short arm of the lever and at the opposite end to the other circuit terminal, and an adjustable pull-off device attached to the end of the long arm of the lever substantially as described.

5. In means for controlling the supply of electric current, the combination with an 105 electric circuit, of a circuit making and breaking device adapted to automatically open and close said circuit and comprising a base; two circuit terminals, one of which presents a contact tip and the other a connecting strip; a lever fulcrumed near one of its ends to provide a long arm and a short arm and carrying a contact tip on its long arm, adapted to normally bear on the contact tip of the first named terminal; a thermo-expansive wire having one end connected to the short arm of the lever and its other end secured to the connecting plate of the second named terminal and adapted to normally exert a pull upon said short arm to automatically close the circuit between the contact tips; and a spring having one end secured to the base and the other attached to the end of the long arm of said lever to exert a pull-off force upon such arm and automatically open the circuit between the contact tips, substantially as described.

6. In means for controlling the supply of electric current, the combination with an 130 electric circuit, of a circuit making and

breaking device comprising a base, a lever in the form of a straight rigid bar fulcrumed in close proximity to one of its ends to the base so as to present a short arm and a long arm 5 which latter carries on one side a contact tip, a terminal post projecting from the base at the side of the lever carrying the tip and presenting a contact tip upon which the contact tip of the lever normally bears, two posts 10 projecting from the base on the other side of the lever and adjacent the end of the long arm thereof, a thermo-expansive wire extending from the short arm of the lever to one of the posts adjacent the end of the long arm

of the lever, a retractile spring extending 15 from the end of said long arm to the other of the posts adjacent such end of the lever, and means for connecting the wires of the circuit to the terminal post and the post to which the thermo-expansive wire is attached. 20

In testimony whereof, I have signed my name to this specification, in the presence of two subscribing witnesses.

GEORGE HENRY.
